(57) **CLAIM**

The ornamental design for a karaoke machine, as shown and described.

DESCRIPTION

FIG. 1 is a front perspective view of a karaoke machine, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view of the karaoke machine, shown in an alternate open state and environment of use. The broken lines in the drawings illustrate the portions of the karaoke machine, which form no part of the claimed design.
